2 SHEETS—SHEET 2.

UNITED STATES PATENT OFFICE.

FRED C. CAMERON, OF CHICAGO, ILLINOIS, ASSIGNOR TO RODGER BALLAST CAR COMPANY, A CORPORATION OF MAINE.

SHAFT-ROTATING MEANS.

1,100,352.

Specification of Letters Patent. Patented June 16, 1914.

Application filed April 11, 1910. Serial No. 554,602.

To all whom it may concern:

Be it known that I, FRED C. CAMERON, a citizen of the United States, and resident of Chicago, in the county of Cook and State of Illinois, have invented a certain new and useful Improvement in Shaft-Rotating Means, of which the following is a description, reference being had to the accompanying drawings, which form a part of my 10 specification.

My invention relates to means for rotating a shaft, and is more especially adapted for use in connection with brakes for railway cars to be operated by hand; the object of the invention being to provide a device that will afford a great leverage when it is desired to apply the brakes, and at the same time present a construction that will normally be in an inoperative position and 20 out of the way of passing objects or out of the way of objects that are being passed by the car on which the mechanism is located.

In the drawings—wherein my invention 25 is illustrated in connection with the rotating shaft of a hand brake—Figure 1 is a perspective view of my invention with the hand lever shown raised in operative position; a portion of the mechanism and lever 30 being broken away. Fig. 2 is a top plan view of the same. Fig. 3 is a side elevation of my invention. Fig. 4 is a longitudinal sectional view taken on the line A—B of Fig. 3, looking toward the right. Fig. 35 5 is a side elevation looking at the right hand or operating lever side of Fig. 3.

The invention is illustrated as applied to the brake shaft on the side of a railway car, 1 being the shaft to be rotated and 40 about which the chain is usually wound. This shaft is suitably mounted on the side of the car, as for example by bracket 2; the shaft, of course, being free to rotate in the bracket.

45 Loosely mounted on the shaft or staff 1, is an operating member 3; the portion of the member encircling the shaft being preferably bifurcated as shown at 4 and 5 to extend about the shaft above and below the 50 bearing portion of bracket 2 and thereby maintain the member in proper position on the shaft; the bifurcated end preventing the member 3 from either dropping down or sliding off of shaft 1.

This member 3 has an operating device 55 in the nature of a lever or drop brake handle 6 pivotally mounted thereon; the lever or brake handle is mounted on the member 3 so as to assume a normal position by gravity, that is, handle 6 is free to drop 60 into a position parallel with shaft 1, as indicated in dotted lines in Fig. 3, when not in operation. The end of this lever or drop brake handle 6 extends beyond the pivotal point to form a cam 7, see Fig. 1 65 and also shown in dotted lines in Fig. 3. Member 3 also has pivotally mounted thereon a gravity-actuated member or pawl 8 whose engaging end swings into operative position by reason of the weight of its free 70 end 9; this free end 9 of the pawl 8 extends downward to be engaged by the cam 7 of the lever or drop brake handle 6, when the latter is dropped to a vertical position. The pawl therefore, in the exemplification, constitutes the means whereby the member 3 is placed into operative relation with shaft or staff 1. Properly secured on the end of the shaft 1 is a ratchet wheel 10 with its teeth 75 presented downwardly as shown, to be engaged by the pawl 8 when the mechanism is in operative position. I have shown the shaft 1 squared to take into the square opening in the hub of ratchet wheel 10, while the end of the shaft may be screw-threaded, as shown, to receive the nut 11 whereby the ratchet wheel 10 is held down into place; and a cotter pin 12 may be employed to prevent the nut 11 from working 80 loose.

Suitably mounted on the frame of the car or other supporting means, is a gravity-actuated pawl 13, arranged to engage with the ratchet 10 and lock the ratchet wheel against rotation in one direction. The free 95 or tail end of this pawl 13 is engaged by the dog 14 which is also mounted on the side of the car. When this dog 14 is dropped down in the position shown in Fig. 3, it engages with the free end of pawl 13 100 and holds the engaging end of the pawl 13 in engagement with the ratchet wheel 10, thereby preventing its rotation and the rotation of the shaft 1 in an opposite direction from that in which the shaft is rotated 105 by said member 3.

The operation of the mechanism is as follows:—When it is desired to rotate the shaft

or staff and apply the brakes, the lever or drop brake handle 6 is lifted into the horizontal position shown in Figs. 1, 2, and 3, thereby swinging cam 7 out of engagement with the free end 9 of pawl 8, allowing pawl 8—by reason of the weight of end 9—to come into engagement with ratchet wheel 10. By swinging lever or drop brake handle 6 in a horizontal direction it is apparent that member 3 will also be moved therewith, thereby forcing ratchet wheel 10 to turn through the engagement of pawl 8 therewith. The turning of ratchet wheel 10, of course, turns shaft 1 in a similar manner and applies the brakes. During this operation dog 14 is placed in the position shown in Fig. 3, that is, in engagement with the free end of pawl 13, thereby swinging this pawl 13 upward into engagement with the ratchet wheel 10, and holding the latter, together with shaft 1, against rotation in the reverse direction. Pawl 13 is of course so mounted as to engage with the ratchet wheel 10 to the opposite sides of that with which pawl 8 engages, so as to be out of the way of this pawl 8 and the oscillating member 3. After the shaft has been rotated sufficiently, lever or drop brake handle 6 is released, permitting it to drop downward into the position shown in dotted lines in Fig. 3; this will bring cam 7 into engagement with the free end 9 of pawl 8 and rock the latter on its pivotal point out of engagement with the ratchet wheel 10, swinging the free end of pawl 8 above its normal horizontal plane, thus placing the mechanism in an inoperative condition. This prevents any accidental operation of the shaft while the lever is in its vertical position. The ratchet wheel 10 together with shaft 1 will be held in the rotated position by the pawl 13 which is maintained in engagement with the ratchet wheel 10 by the dog 14. When it is desired to release the shaft and thereby release the brakes, it is simply necessary to lift dog 14 to a vertical position, permitting pawl 13 to be disengaged from ratchet wheel 10, when the ratchet wheel 10 and shaft 1 are free to rotate back to normal position. As pawl 8 is yieldingly held in engagement with ratchet wheel 10 by the action of gravity, it is apparent that the pawl is free to ride over the teeth of the ratchet during one stroke in the oscillation of the member 3; the shaft being rotated during the other stroke in the oscillation of member 3.

My improved device is illustrated as more especially adapted for use in operating a brake shaft, but it is apparent that it may be employed in other connections; and furthermore, the mechanism may be altered in a number of minor details without departing from the spirit of my invention.

Having thus described my invention, what

I claim and wish to secure by Letters Patent, is:—

1. In combination with a rotatably mounted shaft, a member loosely mounted on said shaft, mechanism intermediate of said member and shaft whereby the two are operatively connected together, and a lever pivotally mounted on said member whereby the latter may be rotated, said lever being arranged to engage with the mechanism and effect the operative connection between said member and the shaft when the lever is released. 70

2. In combination with a shaft adapted to be rotated, a member loosely mounted on said shaft, a second member pivotally mounted on said first member and arranged to automatically move into operative connection with the shaft, and an operating device pivotally connected with said member whereby the latter together with the shaft may be operated. 80

3. In combination with a shaft to be rotated, a member loosely mounted on said shaft and adapted to oscillate about the same, and pivotally mounted gravity-actuated mechanism intermediate of said member and the shaft whereby the latter is rotated during one stroke or oscillation of said member. 90

4. In a device of the class described, a shaft adapted to be rotated, a member loosely mounted on said shaft and arranged to oscillate, mechanism mounted on said member adapted to swing into engagement with said shaft, and a lever pivoted on said member whereby the latter may be oscillated, said lever being arranged to drop into a vertical position and move the mechanism out of operative engagement with the shaft. 100

5. Means for rotating a shaft comprising a member loosely mounted on the shaft to be rotated, an operating device carried by said member and normally depending in an inoperative position, and loosely mounted mechanism arranged to form operative engagement between the member and the shaft when said device is brought up into operative position, and disconnect said engagement automatically when the device is released. 110

6. Means for rotating a shaft comprising a member loosely mounted on the shaft to be rotated, an operating device carried by said member and normally depending in an inoperative position, and mechanism pivotally mounted on said member and adapted to automatically swing into engagement with the shaft when the operating device is brought upward into operative position. 120

7. Means for rotating a brake-shaft comprising the rotatable shaft, a member loosely mounted on said shaft and adapted to be oscillated, a pawl and ratchet connection between said member and the shaft arranged 125

to rotate the shaft during one stroke of said member, the pawl being loosely mounted on said member, a lever pivoted to said member and normally holding said pawl out of engagement with the ratchet, and mechanism adapted to engage with the ratchet whereby the shaft is held against rotation during the idle stroke of the member.

8. In combination with a shaft to be rotated, a member loosely mounted and adapted to oscillate about said shaft, gravity-controlled mechanism mounted on said member and adapted to automatically form operative connection with said shaft, and a lever pivoted to said member and arranged to swing into a position parallel with the shaft to be rotated and thereby move said mechanism out of operative relation with the shaft.

9. In combination with a shaft to be rotated, a ratchet wheel secured on said shaft, a member loosely mounted on said shaft beneath the ratchet wheel and arranged to be oscillated about the shaft, a gravity-actuated pawl mounted on said member and arranged to swing into operative engagement with the ratchet wheel, and a lever pivotally mounted on said member, normally depending in a position parallel with the shaft and holding the pawl out of engagement with the ratchet wheel until the lever is raised into operative position, and means for holding the shaft in its rotated position.

10. In combination with a shaft to be rotated, a member adapted to oscillate about said shaft, means whereby the member may be placed into operative relation with the shaft, a lever pivotally mounted on said member and arranged to engage with said means and automatically control the operative relation between the member and the shaft, and means for automatically holding the shaft against rotation in one direction.

11. In combination with a shaft to be rotated, a member adapted to oscillate about the shaft and arranged to have operative relation with the shaft, a lever pivoted to said member and arranged to control the operative relation between said member and shaft, and gravity actuated means whereby the shaft is locked in position.

12. In combination with a shaft to be rotated, a member loosely mounted on the shaft, a lever pivoted on said member, a pawl carried by said member arranged to form an operative relation between the member and the shaft, and gravity-actuated mechanism whereby the shaft is locked against rotation in one direction.

13. In combination with a shaft to be rotated, a member loosely mounted on and arranged to oscillate about the shaft, a pawl carried by said member whereby one stroke or oscillation of the member will rotate said

shaft, a lever pivoted to said member normally depending beneath the member and holding the pawl out of operative position, and gravity-actuated mechanism whereby the shaft is locked against rotation in one direction.

14. In combination with a shaft to be rotated, a member loosely mounted and adapted to oscillate about said shaft, mechanism carried by said member whereby a yielding connection between the member and the shaft may be established, a gravity actuated lever pivoted to said member and arranged to automatically break said yielding connection when the lever is released, means whereby said member is held in position on the shaft, and gravity-actuated locking mechanism whereby the shaft is held against rotation in one direction.

15. The combination with a rod or staff having a ratchet thereon, a pivoted pawl lever for engagement with the ratchet, and a drop brake handle having a cam portion adapted to free the pawl from the ratchet by its dropping movement, substantially as described.

16. The combination with a rod or staff having a ratchet and a pivoted pawl device for engagement with the ratchet, of a pivoted handle having a horizontal operative position and a dropped vertical normal position, the handle being mounted to assume a normal position by gravity and also having a portion arranged to effect the release of the pawl from the ratchet when the handle is dropped, substantially as described.

17. The combination with a rod or staff having a ratchet thereon, a pawl lever for engagement with the ratchet, and a drop brake handle having a cam portion adapted to free the pawl from the ratchet by its engagement with said pawl when the handle drops by gravity, substantially as described.

18. Brake actuating mechanism including a brake staff, a ratchet wheel secured thereto, a pawl for engaging the said ratchet wheel, means for supporting the said pawl, a brake applying lever having pivotal connection with the said means and which lever is adapted to occupy either a vertical or a horizontal position, and the said lever being provided with means beyond its pivot for engaging the said pawl to retract the same to disengage it from the said ratchet wheel when the said lever is dropped into vertical position, and means for moving the said pawl into engagement with the said ratchet wheel when the said lever is moved into horizontal position.
